GEORGE W. LINDLEY, OF PHILADELPHIA, PENNSYLVANIA.

KNITTING MACHINE.

Application filed February 8, 1926. Serial No. 86,710.

This invention relates generally to knitting machines for producing ribbed fabric with elastic inlay yarn incorporated in its meshes. From a more specific point of view, it is concerned with circular knitters of a type adapted to the manufacture of therapeutic garments such as stockings, abdominal supports, belts, etc.

In connection with the knitting machines 10 of the special class referred to, I seek to provide very simple and reliable mechanism whereby the elastic inlay yarn is fed directly to the knitting needles with avoidance of twisting and its tension may be varied either 15 under manual or automatic control, and the size of fabric loops formed with the knitting yarn concurrently graduated for the purpose of fashioning or shaping the garments—particularly with regard to formation of 20 circumferential protuberances, for example, knee pockets in hosiery.

The several mechanical improvements collectively contributing to the attainment of the desiderata above outlined, together with 25 special advantages accruing to them individually, will appear from the detailed description of the typical embodiment of my invention shown on the drawings herewith.

Fig. I is a plan view of the complete machine.

Fig. II is an elevation of the front of the structure.

Fig. III is a view, in side elevation, of the feed means for the elastic yarn on a larger 35 scale than shown in the preceding illustrations.

Fig. IV is a detail section taken as indicated by the arrows IV—IV in Fig. III.

Fig. V is a view taken as indicated by the 40 arrows V—V in Fig. II.

Fig. VI is a section taken along the line VI—VI in Fig. I.

Fig. VII is a detail section view, taken as 45 designated by the arrows VII—VII in Fig. II.

Fig. VIII, is a diagrammatic illustration showing a linear development of the cam ring and the means by which the stitch drawing cam is controlled for fashioning purposes 50 in accordance with my invention.

Fig. IX is an inverted fragmentary plan

view showing certain elements embodied in the means depicted in the preceding illustration; and,

Fig. X is a detail view of the measuring 55 chain showing the cam lugs for automatically controlling the feeding means for the elastic yarn and governing the belt shipper of the machine.

The cylinder 15 of the machine is rotatable 60 in the bed plate 16; and the cams for actuating the cylinder needles N are supported internally of a fixed ring 17 that surrounds said cylinder. The associated ribbing dial 18, together with its horizontal needles N' and the cam plate 19 for actuating them, is suspended axially of the cylinder 15 from a bridging bar 20 that spans the knitting head, said cam plate being held against rotation by a bracket 21 with set screws 22 engaging the bridging 70 bar 20 from opposite sides. The usual knitting yarn indicated Y is directed to the needles N enroute from a source of supply (not shown) through a guide 23 fast on the cam plate 19; while the elastic inlay yarn designated Y' is fed through the eye of a guide 24 adjustable on a post 25 secured to the cam ring 17. A bevel gear 26 formed on a depending annular flange of the needle cylinder 15 is driven by an intermeshing pinion 27 on the 80 inner end of the drive shaft 28 which is equipped with the usual tight and loose pulleys 29, 30, respectively, see Figs. I and II. The belt shipper 31 is pivoted by a fixed stud 32 on the machine frame 33, and has an arm 85 34 that projects inwardly for engagement beneath the depending extremity 35 of the right angled trip lever 35 whereby said shipper is normally held, in the position shown in Fig. II, in opposition to a compression 90 spring 36. The trip lever 35 is swingable at right angles to the belt shipper 31 about a fixed center 37, and is normally held in the position shown under upward pull exerted by a helical spring 38, see Fig. II.

At the end opposite that occupied by the pulleys 29, 30, the machine has a laterally projecting bracket 39 upon which is mounted a sprocket wheel 40 for a measuring chain 41 that carries cam lugs 42, 43 at opposite sides 100 thereof, see Fig. X, for a purpose to be later explained. The chain 41 also carries one or

more center lugs 44, which, through interposed parts about to be described, are instrumental in automatically stopping the machine. An angle lever 45 pivotally secured at 46 to a bracket 47 rising from the bed plate 16 has one end thereof lying in the path of the central cam lugs 44 of the chain 41, and its opposite end engaging a pin 48 upstanding from a second lever 49 which is fulcrumed to 10 swing horizontally about a fixed stud 50 on said bed plate. The opposite extremity of the lever 49 is subject to a spring 49^a, and normally engages a circumferential groove 51 in a vertical slide rod 52, having bearing in 15 the bed plate 16 and in an upstanding bracket 53 on the latter. A spring 54 (Fig. II) tends to urge the slide rod 52 downwardly when released by inward movement of the lever 51, thereby to depress the horizontal arm 35^b of 20 the right angled trip lever 35 and swing the latter to release the belt shipper 31.

Intermittent movement of the measuring chain 41 is effected by pawling mechanism including an arm 55 which is mounted for free 25 oscillation on the sprocket wheel axis 56 and carries a pawl 57 adapted to pick the teeth of a ratchet wheel 58, secured to the sprocket 40 at one side. The pawl arm 55 is vibrated by virtue of a link connection 59 with a rocker 30 arm 60, fixed to a shaft 61 having bearing in the projecting bracket 39. At its inner end the shaft 61 has secured to it a second arm 62 with a roller 63 thereon, which lies in the path of a cam 64 on the take-up frame 65, rotating 35 with the needle cylinder 15.

The means which I provide for maintaining variable tension on the elastic yarn Y' during its feeding includes a pair of cooperative rotating members, one having the form 40 of a disk 66, see Figs. I-IV, and the other the form of a friction roller 67 running in contact with said disk, the yarn Y' being passed between the two on its way to the guide 24, previously mentioned. The drive disk 66 is located eccentrically of the knitting head, its shaft being journaled in a bracket 68 that is bolted or otherwise positionally fixed adjacent the periphery of the bed plate 16. Continuous rotative movement is imparted to the drive disk 66, from the bevel gear 26 on the needle cylinder 15, through a system of coordinated bevel gears indicated at 69, 69, in Fig. I. The friction roller 67 is journaled in a follower 70 which is shiftable radially of the drive disk 66 by a screw 71 rotatable in the upright portions 72 of a bearer extension 68^a of the bracket 68 above referred to, a guide rod 73 also supported by said bearer serving to hold the follower 70 to such course while preventing rotation thereof with the screw 71. From Fig. IV it will be noted that the follower 70 comprises a block 74 which is apertured for traverse on the screw 71 as well as along the guide rod 73, and a yoke piece 75 that is vertically slid-

able on the block 74 to enable lifting of the roller 67 from the disk 66 when threading the elastic yarn Y'. The friction roller 67 is held in pressure contact with the drive disk 66 by a spring 76 which encircles an upward 70 rod extension 77 of the block 74, and it is in compression between a head 78 at the upper end of said rod and the top cross bar 75^a of the yoke. As an aid in raising the friction roller 67 and holding it elevated during 75 threading, I provide an eccentric cam 79 which is rotatable on the yoke 75 by means of an integral finger knob 80, and has its periphery engaging the top of the block 74. Guides 81, 82 secured to opposite sides of the 80 yoke 75 cooperate in holding the elastic yarn Y' to a central course beneath the roller 67, and a circumferential groove 67^a in the latter prevents displacement of said yarn as the follower 70 is moved radially of the drive disk 85 66. A knurled finger knob 83 on one end of the screw 71 facilitates initial setting of the follower 70 in any desired position relative to the drive disk 66; and a graduated scale 84 (Fig. I) is provided for coordination with a pointer 85 on said follower to assist in such setting.

The office of controlling actuation of the screw 71 is relegated to mechanism that comprises right and left hand ratchet wheels 86, 87 secured side by side on a shaft 88 that is journaled in the bracket 47 hereinbefore mentioned, and a bevel gear 89 also secured thereon drives a similar gear 90 on the screw 71, the latter of the two gears being subject to 100 a brake having, as shown in Fig. III, the form of a friction plate 91 with screw means 91^a whereon its pressure may be varied, as required. A yoke 92, mounted for independent rocking movement on the shaft 88, carries 105 a pair of pawl elements 93, 94 arranged for cooperation respectively with the ratchets 86, 87. These pawl elements 93, 94 are bifurcated as at 93^a, 94^a to engage over the ratchets 86, 87; and the crotches of the bifurcations are 110 oppositely sloped, as shown in Figs. II and VI, to fit the notches of the ratchets 86, 87 with which they are respectively associated. The outward rod prolongations 93^b, 94^b of the 115 pawl elements 93, 94 are guided for longitudinal sliding in a head 92^a formed on the horizontal cross bar of the yoke 92, surrounding springs 95, housed within coaxial cavities in the head, functioning to urge the pawl elements 93, 94 yieldingly toward the ratchets 120 86, 87. The yoke 92 is oscillated through a link connection with a bell crank arm 96 which is free on the shaft 61 (Fig. II) and carries at the end of its shorter extremity, a roller 97 adapted to be engaged by the same 125 cam 64 that actuates the roller arm 62 of the pawling mechanism for the measuring chain 41. To the end of rendering the action of the ratchets 86, 87 selective, independently 130 actuatable pawl guards are provided, these 135

being in the form of levers 98, 99 that are centrally fulcrumed on a common stud 100, on the bracket 39. The inner ends of the levers 98, 99 are curved as at 98^a, 99^a to 5 vide rounded edges over which the pawl elements 93, 94 normally ride idly back and forth, during oscillation of the yoke 92, while being held away from the ratchets 86, 87. Springs 101, 102 in tension between a fixed 10 anchorage 103 on the bracket 39, and the opposite extremities of the pawl guard levers 98, 99, serve to normally maintain the levers, in said positions shown in Figs. I and VI, with both pawl elements 93, 94 raised to 15 active position. In automatic operation of the machine, the pawling is governed by the cam lugs 42, 43 of the measuring chain 41, which, in passing beneath the pawl guard levers 98, 99, alternately engage tappet blocks 20 104, 105 adjustably set on the latter.

Provision is also made for manually controlling the pawling so that the tension at which the elastic yarn Y' is fed during knitting of different portions of a garment 25 may be varied in accordance with special specifications. The means to this end includes a pair of rotary cams 106, 107 (Figs. I-II) that underlies the outer ends of the pawl guard levers 98, 99, said cams being secured 30 to a common shaft 108 which is journaled in a terminal boss of the bracket 39 and equipped with an actuating handle 109. The rotary cams 106, 107 are so positioned angularly on the shaft 108 that swinging of the handle 109 35 to opposite sides of a vertical neutral position results in the actuation of one or the other of the guard levers, 98, 99, and, as a consequence, pawling of the respectively coordinated ratchet wheels 86, 87. Any suitable means 40 may be employed to hold the actuating handle 109 in the vertical neutral position or the two horizontal positions, for example a sector 110 which is affixed to the bracket 39 and has properly spaced indentations 110^a, 110^b, 110^c 45 for seating of a spring pressed ball (not shown) in said handle, as well as stops 110^d, 110^e that limit the throw of the latter.

For the purpose of enabling formation of circumferential protuberances in the work 50 produced by the machine, I resort to the means shown in detail in Figs. VIII and IX. This means is operative upon the stitch drawing cam 115 (Fig. VIII) for the cylinder needles, said cam being mounted with 55 capacity for vertical adjustment in the cam ring 17. Projecting outwardly from the cam 115 through a slot 116, in the wall of the cam ring 17, is a stud 117 that is engaged by a screw 118 adjustably set in one end of an 60 arcuate lever 119, see Figs. I and II in connection with Fig. VIII, having its fulcrum on a screw 120, let into the cam ring 17. The opposite end of the arcuate lever 119 extends laterally outward to overlie a pin 121, slide- 65 able vertically in an aperture adjacent the

periphery of the bed plate 16. A compression spring 122, operative against a head on the lower end of the pin 121, maintains the latter in engagement with one extremity of a centrally-fulcrumed rocker arm 123 with 70 bearing in a bracket 124, depending from the bed plate 16. A roller 125 mounted on a stud 126, in the opposite extremity of the rocker arm 123, is adapted to run in contact with the profile edge of a cam ring 127 that 75 surrounds the annular bevel gear 26 at the bottom of the needle cylinder 15. Thus, as the needle cylinder 15 is rotated, the rocker arm 123 is moved up and down in accordance with the profile edge of the cam ring 127, 80 the movement being transmitted to the stitch drawing cam 115 and the length of the stitches drawn by the needles correspondingly graduated in each successive course of the knitting. The stitch drawing cam 115 control means can be rendered inoperative by withdrawing the cotter pin 128 (Fig. IX) from the aperture 129 in the stud 126 of the rocker arm 123, shifting the roller 125 to the dotted line position, and inserting the pin 90 128 in a second hole 130 in said stud to hold the roller 125 retracted.

Briefly described, the operation of the machine is as follows: Let it be assumed that the machine is running, i. e., the needle cylinder 15 rotating in the direction of the arrow on Fig. I, the knitting yarn Y being drawn in the usual way to satisfy the requirements imposed by the activity of the needles N, N', and the elastic yarn Y' following suit, though 95 subject to tension as a result of its restrained travel between the friction roller 67 and the drive disk 66. As the measuring chain 41 is progressed step by step under the action of the pawling mechanism for the sprocket 105 wheel 40, and as the cam lugs 42 thereon are brought into play, the pawl guard lever 98 is successively actuated to release the corresponding pawl element 93 with the result that the screw 71 is rotated counter clockwise 110 and the follower 70 moved radially inward of the drive disk 66 by degrees to gradually increase the tensional restraint on the elastic yarn Y'. When the other side or cam lugs 43 of the measuring chain 41 are active, the 115 above operation is reversed—that is to say—the screw 71 is progressively rotated clockwise through actuation of the pawl guard lever 99 and the intermediate coordinated parts, so that the follower 70 is moved toward 120 the periphery of the drive disk 66 to decrease the tensional restraint on the elastic yarn Y'. By proper arrangement of the cam lugs 42, 43 on the measuring chain 41, it will be apparent that the product of the machine may 125 be automatically fashioned to any shape desired or required.

When special conditions are prescribed, the fashioning may be controlled manually, by first turning the pawl 57 about its pivot and 130

over upon its back, as shown in dotted lines in Fig. II, to prevent operation of the measuring chain 41. Then, by selectively actuating the pawl guard levers 98, 99 with the aid of the handle 109, either clockwise or counterclockwise movement of the screw 71 may be predetermined to correspondingly increase or decrease the tension on the elastic yarn Y' as required, the latter operation being greatly facilitated with the aid of the graduated scale 84 and the cooperating pointer 85, on the follower 70. When special work such as above mentioned is to be produced, it is desirable that the machine be automatically brought to a stop after the straight way portions of the tube are knit and preparatory to manual manipulation of the tension control. It is to this end that center lugs, such as shown at 44 in Fig. X are provided on the measuring chain 41, movement of the angle lever 45—occasioned by engagement of one of said lugs 44—being imparted to the coordinated levers 45, 49 to cause retraction of the inner end of the latter from the vertical slide rod 52, which, upon release, is urged downward by the spring 54 to actuate the trip lever 35 associated with the belt shipper 31. The shipper 31 being thus freed, is immediately swung about its pivot 32 by the spring 36, to transfer the drive belt to the loose pulley 30. When the necessary preparations have been made for the purpose stated, the machine may be restarted by resetting the belt shipper 31 and its tripping mechanism to the positions shown in the drawings.

The mechanism of Fig. VIII for varying the size of the fabric loops may be brought into play by shifting the roller 126 into the province of the profile cam ring 127 surrounding the depending annular bevel gear 26 of the needle cylinder 15, whereupon, with each rotation of the machine, the fabric loops are graduated around the tube, the result of the procedure being the formation of a circumferential protuberance configured in accordance with the profile edge of the ring. Loop fashioning, such as just described, may of course be modified by concurrently varying the tension at which the elastic yarn Y' is fed—under either manual or automatic control—with the mechanism provided herein for the purpose.

Having thus described my invention, I claim:

55 1. In knitting machines for producing tubular fabric with elastic yarn incorporated in its meshes and having a rotating needle cylinder, a shiftable stitch cam, and means to raise and lower the stitch cam incidental to rotation of the needle cylinder, thereby to vary the length of the fabric loops drawn by the needles in each course of the knitting concurrently with feeding of the elastic yarn under tension.

65 2. In knitting machines for producing tu-

bular fabric with elastic yarn incorporated in its meshes and having a rotating needle cylinder, a shiftable stitch cam, a profile cam ring rotating with the needle cylinder instrumental in causing the stitch cam to be moved up and down during each rotation of the machine in accordance with the profile configuration of said ring, thereby to vary the length of the fabric loops drawn by the needles in the corresponding course of the knitting, concurrently with feeding of the elastic yarn under tension.

3. In knitting machines for producing tubular fabric having elastic yarn incorporated in its meshes and having a rotating needle cylinder, a shiftable stitch cam, a profile cam ring rotating with the needle cylinder, an interposed element for imparting up and down movement to the stitch cam during each rotation of the machine in accordance with the profile configuration of said cam ring thereby to vary the length of the fabric loops in the corresponding course of the knitting concurrently with feeding of the elastic yarn under tension, and means whereby the element aforesaid may be rendered inactive.

4. In knitting machines for producing fabric with elastic yarn incorporated in its meshes, means for feeding the elastic yarn comprising a pair of contacting rotary members rotating at right angles to each other and between which the yarn is passed, and means whereby said members may be relatively shifted to vary the degree of restraint on the elastic yarn.

5. In machines for producing knitted fabric with elastic yarn incorporated in its meshes, feeding means for the elastic yarn including a drive disk and a contacting driven roller between which the yarn is passed, said roller being radially shiftable with respect to the disk to vary the rate of feeding and provided with a circumferential groove to prevent relative lateral displacement of the yarn during such shifting.

6. In machines for producing knitted fabric with elastic inlay yarn incorporated in its meshes, means for feeding the elastic yarn comprising a drive disk, a feed roller adapted to run in pressure contact with the drive disk and beneath which the yarn is passed, a support in which the roller is journaled with capacity for being retracted to enable threading, and means to shift the roller support radially of the drive disk for the purpose of varying the rate of feeding of the yarn.

7. In machines for producing knitted fabric with elastic yarn incorporated in its meshes, the combination of a rotating needle cylinder, and means for feeding the elastic yarn comprising a revolving drive disk stationarily mounted eccentrically of the needle cylinder, and a feed roller shiftable radially of the revolving disk while running in con-

tact therewith to vary the rate at which the elastic yarn is fed.

8. In machines for producing knitted fabrics with elastic yarn incorporated in its meshes, the combination of a rotating needle cylinder, and means for feeding the elastic yarn comprising a revolving drive disk stationarily mounted eccentrically of the needle cylinder, a feed roller running in contact with said disk, and a screw for shifting the roller radially of the disk to vary the rate at which the yarn is fed.

9. In machines for producing knitted fabric with elastic yarn incorporated in its meshes, the combination of means for feeding the elastic yarn comprising a revolving drive disk, a feed roller running in contact with the disk, a screw for shifting the roller radially of said disk to vary the rate at which the yarn is fed, and control mechanism for turning the screw in opposite directions for the purpose specified, including right and left hand ratchet wheels, and means for independently governing actuation of said ratchet wheels.

10. In machines for producing knitted fabric with elastic yarn incorporated in its meshes, the combination of feeding means for the elastic yarn comprising a revolving drive disk, a feed roller running in contact with the disk, a screw for shifting the roller radially of the disk to vary the rate at which the yarn is fed, and control mechanism for turning the screw in opposite directions for the purpose specified, including right and left hand ratchet wheels, guards associated with the pawls of the ratchets, and means whereby said guards may be selectively actuated to govern action of the ratchets.

11. In machines for producing knitted fabric with elastic yarn incorporated in its meshes, the combination of feeding means for the elastic yarn comprising a revolving drive disk, a feed roller running in contact with the disk, a screw for shifting the roller radially of the disk to vary the rate at which the yarn is fed, and control mechanism for turning the screw in opposite directions for the purpose specified, including right and left hand ratchet wheels, pivoted guards associated with the pawls of said ratchets, and operative rotary cam means enabling selective actuation of the pawl guards to govern movement of the ratchets.

12. In machines for producing knitted fabric with elastic yarn incorporated in its meshes, the combination of feeding means comprising a revolving drive disk, a feed roller running in contact with the disk, a screw for shifting the roller radially of the disk to vary the rate at which the elastic yarn is fed, and control mechanism for turning the screw in opposite directions for the purpose specified, including right and left hand ratchet wheels, pivoted guards associated with the pawls of the ratchets, and rotary

cams enabling selective actuation of pawl guards, said cams being mounted on a common shaft equipped with an operating handle.

13. In machines for producing knitted fabric with elastic yarn incorporated in its meshes, the combination of means for feeding the elastic yarn comprising a drive disk, a feed roller running in contact with the disk, a screw for shifting the roller radially of the disk to vary the rate at which the yarn is fed; and control mechanism for turning the screw in opposite directions for the purpose specified, including right and left hand ratchet wheels, pivoted guards for the pawls of the ratchets, and a sprocket chain with high links for independently actuating the pawl guards to govern the ratchets.

14. In a knitting machine for producing fabric with incorporated elastic inlay yarn and having a rotating needle cylinder means including a pair of revolving elements on axes at right angles to one another for continuously feeding the elastic yarn to the needles under predetermined tension and with avoidance of twisting, said means being supported independent of the needle cylinder.

15. In a knitting machine for producing fabric with incorporated elastic inlay yarn and having a rotating needle cylinder, means including a pair of revolving elements on axes at right angles to one another for continuously feeding the elastic inlay yarn under predetermined tension and avoidance of twisting, said means being supported independent of the needle cylinder, and means for altering the operative relation between the rotating elements aforesaid to graduate tension of the elastic yarn.

16. In a knitting machine for producing fabric with incorporated elastic inlay yarn and having a rotating needle cylinder, means including a pair of revolving elements on axes at right angles to one another for continuously feeding the elastic inlay yarn under predetermined tension and avoidance of twisting, said means being supported independent of the needle cylinder, and automatic mechanism controlling the means aforesaid to vary the tension at which the elastic yarn is fed.

17. In a knitting machine for producing fabric with incorporated elastic inlay yarn and having a rotating needle cylinder, means including a pair of revolving elements on axes at right angles to one another for continuously feeding the elastic inlay yarn under predetermined tension and avoidance of twisting, said means being supported independent of the needle cylinder, and means to effect graduated variation in the loops drawn by the needles incidental to feeding of the elastic yarn.

18. In a knitting machine for producing fabric with incorporated elastic inlay yarn and having a rotating needle cylinder, means

including a pair of revolving elements on axes at right angles to one another for continuously feeding the elastic inlay yarn under predetermined tension and avoidance of twisting, 5 said means being supported independent of the needle cylinder, and means to effect graduated variation in the loops drawn by the

needles in segmental portions of the fabric incidental to feeding of the elastic yarn.

In testimony whereof, I have hereunto 10 signed my name at Philadelphia, Pennsylvania, this 5th day of February, 1926.

GEORGE W. LINDLEY.
